ATTORNEY.

UNITED STATES PATENT OFFICE.

HERMAN F. D. CROWNFIELD, OF BALTIMORE, MARYLAND, ASSIGNOR OF ONE-HALF TO FRANCIS X. GANTER, OF SAME PLACE.

COMBINED LATCH AND LOCK.

SPECIFICATION forming part of Letters Patent No. 366,998, dated July 19, 1887.

Application filed May 31, 1887. Serial No. 239,798. (No model.)

To all whom it may concern:

Be it known that I, HERMAN F. D. CROWNFIELD, a citizen of the United States, residing at Baltimore, in the State of Maryland, have 5 invented certain new and useful Improvements in a Combined Latch and Lock, of which the following is a specification.

My invention relates to an improved latch and lock, and is illustrated in the drawings 10 annexed, in which—

Figure 1 is a view of the back of the latch, the back plate, *h*, thereof being removed to afford a better view of the mechanism. Figs. 2 and 3 are sections of the latch without the 15 knobs, taken on the lines 2 and 3, respectively, shown in Fig. 1. Fig. 4 is a front view of the latch. Fig. 5 is a view of the bolt. Figs. 6 and 7 are views of the knob-shaft.

The letter *A* designates the latch case, *B* the 20 bolt, and *C* the knob-shaft. The bolt *B* has a bifurcated or two-arm shank, *b b'*, with an open central space, *c*, between the arms of the bifurcation. Each arm has at its extremity a flange, *d*, and an incline, *e*, which is highest 25 near said flange and deepens as it proceeds toward the bolt end. The bolt has near its head a small socket, *f*, in its side. The case *A* is provided on its inner side with a central boss, *g*, which has a screw-hole, *g'*, for a screw, *g''*, which serves to confine the back plate, *h*, which latter rests on the boss *g* and shoulders *x*. The 30 two arms *b b'* of the bolt-shank pass on either side of the boss *g*, while the latter is fixed in the central space, *c*, between the said two arms. A spiral-spring, *i*, also occupies the central 35 space, and has one end against the boss *g* and the other end against the bolt. This spring serves to press the bolt out or keep it "shot," as in Fig. 1.

The knob-shaft *C* has a round or cylindrical head, *k*, which occupies loosely a round bearing or hole, *l*, in the lock-case, and a similar hole, *l'*, in the back plate, *h*. The relative position of the two bearing holes *l l'* is such that 40 each of the two arms *b b'* of the bolt-shank will pass on an opposite side of the knob-shaft head *k*. The knob-shaft head *k* has at its center two lugs, *m*, projecting in opposite directions, and each lug bears on a different one of 45 the bolt-shank arms *b b'*. These lugs *m* are to act on the flange *d* at the extremity of the bolt-shank arms *b b'*, and also on the inclines *e* of said arms. The knob-shaft *C* thus constructed is capable of two movements—the ordinary rocking movement (that is, a partial 50 turning or rotary back and forward movement) and an endwise movement. This will be readily seen from the drawings, as the round head *k* of the shaft *C* may both turn and also slide in the two bearing holes *l l'*. When the 55 knob-shaft *C*, is partly turned either way, one of the lugs *m* will bind on one of the flanges *d* of the bolt-shank arms, and thereby withdraw the bolt *B*, and when said shaft is moved endwise, so that the two lugs *m* are brought to 60 bear against the inclines *e* of the bolt-shank arms, the bolt *B* will be withdrawn. It will therefore be seen that either one of the two 65 movements of the knob shaft *C* has the effect of withdrawing the bolt, and that the bolt-spring *i* forces the bolt out. A spring, *n*, surrounds the round head *k* at one side of the lugs *m*, and bears against the case *A*, and tends to keep the knob-shaft *C* pressed endwise 70 in such direction that the two lugs *m* will be 75 moved away from the inclines *e*. The lugs *m* are always in position to act on either the flanges *d* or the inclines *e*. A small stop-bolt, *f'*, has position on the inside of the case *A*, and is adapted to take into the socket *f* in the side 80 of the bolt when said bolt is shot or forced out. This stop-bolt *f'* serves to keep the bolt *B* from moving back, and may be employed whenever it is desired to have the said bolt *B* serve as a lock. The stop-bolt *f'* is actuated 85 by a knob, *o*, on the outside of the case, and a shank, *o'*, passes through a slot in the case and connects the knob with the stop-bolt. A small spring, *p*, (see Fig. 3,) is suitably arranged between the stop-bolt and case, and 90 serves to prevent the stop-bolt from slipping. The extremity of the bolt *B* has the usual beveled side, *q*, and the opposite side, *r*, is slightly rounded as it approaches the end. This 95 rounded side will bear against the ordinary catch, which is fixed to the door-frame and facilitates the entrance of the bolt end into the catch. This is found desirable when closing the door by pulling the knob-shaft. A latch thus constructed may have its bolt drawn back 100

into the case by partly turning the knob-shaft or by pushing or pulling said knob-shaft. With this lock a person whose hands happen to be full of packages or bundles, and therefore 5 is unable to turn the knob, may, nevertheless, be able to push or pull the knob, and thus open the door.

Having described my invention, I claim and desire to secure by Letters Patent of the United 10 States—

1. An improved combined latch and lock, consisting of the bolt B, having bifurcated portion b b', inclines e e, flanges d d, rounded portion r, and socket f, the spring i, the casing A, 15 with boss g, the knob-shaft C, with head k, having lugs m m, the spring n, surrounding

said head, and the stop-bolt f', having spring p and knob o, said bolt f' adapted to engage the socket of the bolt B, as shown and described, and for the purpose set forth. 20

2. In a combined latch and lock, the bolt B, having a socket, f', in its side, in combination with the spring stop-bolt having knob o, the the said stop-bolt adapted to enter said socket in the bolt and thereby lock it in position, as 25 shown and described.

In testimony whereof I affix my signature in the presence of two witnesses.

HERMAN F. D. CROWNFIELD.
